UNITED STATES PATENT OFFICE.

ISAAC V. HOLMES, OF CHICAGO, ILLINOIS.

STEAM-GENERATING APPARATUS.

SPECIFICATION forming part of Letters Patent No. 743,386, dated November 3, 1903.

Application filed October 30, 1902. Serial No. 129,421. (No model.)

To all whom it may concern:

Be it known that I, ISAAC V. HOLMES, a citizen of the United States, residing in the city of Chicago, in the county of Cook and State of Illinois, have invented certain new and useful Improvements in Steam-Generating Apparatus, of which the following is a specification.

My invention relates to steam-generating apparatus; and its objects are to preserve the life and maintain the efficiency of a boiler.

To these ends it consists in means for purifying boiler-water and causing a forced circulation of water within the boiler, in means whereby the amount of water purged may be regulated and its circulation within the boiler controlled, and in means whereby the water within the boiler and not transformed into steam may be purged and repurged continuously; and it further consists in the features of construction and combination hereinafter more fully described, and pointed out in the claims hereto annexed.

Referring to the accompanying drawings, wherein like reference-letters indicate the same or corresponding parts, Figure 1 is in part a sectional view and in part an elevation. Fig. 2 is in part an enlarged longitudinal sectional view of the member L, which member is hereinafter more fully described. Fig. 3 is a cross-sectional view taken on line 3 3 of Fig. 2 and viewed in the direction indicated by the arrows at the extremities of said line. Fig. 4 is a cross-sectional view taken on the line 4 4 of Fig. 2 and viewed in the direction indicated by the arrows at the extremities of said line.

Impurities are held in solution in cold water by reason of the gases and fixed air therein. When the water is sufficiently heated, the air and gases are freed therefrom, and the impurities then become in suspension. These and the other impurities which were in suspension in the cold water will either sink therein or rise toward its surface, accordingly as they are of greater or of less specific gravity than the water. When this action takes place within a boiler, if the impurities are not removed therefrom before they can find lodgment on the walls thereof they will form mud or scale, or both, and, according to their nature, thickness, and location within the

boiler, will impair its efficiency and shorten its life. When the above-described action takes place within a feed-water heater, the 55 impurities are in all forms of devices heretofore known to the art carried with the water from the heater to the boiler, in which latter they will be deposited in the form of mud or scale, or both, as they would if the action 60 first took place within the boiler, as hereinbefore described. To maintain the efficiency and preserve the life of a boiler, thereby rendering it possible to obtain the best results from the use thereof, the feed-water should 65 be purged of its impurities before being delivered to the boiler, a positive forced circulation of the water within the boiler should be created and maintained, and the supply of purged water to and its circulation within 70 the boiler should be controllable.

In a separate application herefrom, filed simultaneously herewith and serially numbered 129,420, I have shown, described, and claimed an apparatus adapted to accomplish 75 each and all of the above-stated requirements. Hence I do not claim herein the matter claimed in said application; but in order to even more effectively accomplish the objects of this present invention I have provided additional purging means whereby the gases and fixed air in the water proceeding to the boiler shall be eliminated therefrom and the impurities in solution in the water shall be brought into suspension before the 85 water is delivered to the final purging device.

Referring to Fig. 1 of the drawings, A indicates a boiler; B, a dish or skimmer; C, a pipe connection communicating at one of its ends with the water at or approximate to the 90 surface W thereof within the boiler and at its other end with the pipe connection J and the combined mixer and eliminator L in manner substantially as shown in the drawings; D, a centrifugal separator, which separator is 95 adapted (in the manner hereinafter more fully described) to eliminate suspended impurities from water passing through it, whether said impurities be of greater or of less specific gravity than the water; D⁶, a passage for the exit of purged water from the separator, communicating at one end with the exit end of the drum of the separator and at its other end with the worm-pump E; F, a

pipe connection communicating at one of its ends with the exit end of the pump E and at its other end with the feed-water-receiving space G within the boiler; H, a feed-pump of any suitable kind; h, a pipe communicating with the exit end of the pump H and with the feed-water heater I, which heater may be of any desired kind; J, a pipe connection communicating at one of its ends with the water-delivery end of the feed-water heater I and at its other end with the receiving end of the mixer L; K, a pipe connection communicating at one of its ends with the steam space or dome of the boiler and at its other end communicating with and preferably projecting into the pipe connection J in manner substantially as shown in Fig. 1, which end preferably terminates in a steam-jet or conical member K, adapted to form a steam-jet; L, a member adapted in manner hereinafter more fully described to thoroughly mix water proceeding from the feed-water heater through the pipe J and water proceeding from the boiler through the pipe C to said member and to eliminate gases and air freed from said water; M, a pipe connection communicating at one of its ends with the water-discharge end of the member L and at its other end with the water-receiving end of the separator D.

Assuming that the various pipe connections mentioned are open to their respective points of communication, that the pump H is operating to deliver to and expel from the feed-water heater I five thousand pounds of water per hour, that said heater is sufficiently heating that amount of water in the time stated, that the boiler is filled with purged water to the level W, (shown in dotted lines in the drawings), and that the electric motor d¹³, which revolubly controls the drum d of the separator D, is revolving at a speed of, say, one thousand revolutions per minute, the operation of this form of my device is as follows: Water from the heater passes through the pipe connection J to the receiving end of the mixer L, thence through the pipe connection M to the interior of the revolving drum d of the centrifugal separator D, whence, rid of its contained impurities, it will pass through the passage d⁶ to the pump E, which will thereafter discharge it through the pipe connection F into the feed-water-receiving space G within the boiler, where it will mingle with the water therein. In passing through the mixer L the gases and fixed air are eliminated from the water. Hence when the water reaches the drum of the separator the impurities will be in suspension therein. Being acted upon by the separator these impurities will be eliminated from the water. It will be seen that in this manner the feed-water is thoroughly purged before being delivered to the boiler. The capacity of the pump E we will assume to be seven thousand five hundred pounds of water per hour. Hence it will be seen it has a capacity of two thousand five

hundred pounds of water per hour in excess of the capacity of the pump H. The result of the operation of the pump E is therefore to create a suction of two thousand five hundred pounds of water per hour through the pipe connection C, thence through the mixer L to the receiving end of the drum d of the separator, whence it will be drawn by the pump and delivered to the water-receiving space G within the boiler. In passing through the mixer and the separator it is of course purged in the same manner as the water proceeding from the feed-water heater. Thus it will be seen that as the water within the boiler was or had been purged previously to its being drawn through the pipe connection C from the boiler it will be again purged after passing through the pipe C, as described, and that this purging and repurging will continue as long as the controlling members are free to operate. It will also be seen that the quantity of water drawn from the boiler and returned thereto will be greater than that stated if the amount of water proceeding from the heater to the boiler is lessened. Thus if two thousand five hundred pounds of water per hour proceeds from the heater to the boiler five thousand pounds of water per hour will be drawn from and redelivered to the boiler by the pump E. The "drawing off" of the surface water of the water within the boiler and the returning of it (purged) to the feed-water-receiving space within the boiler creates a positive forced circulation of the water within the boiler. This forced circulation and the quantity of water purged may be increased or diminished by increasing or diminishing the speed of the motor and of the pump E or by suitably adjusting the valves (not shown) which respectively control the passage of the water through the pipe connections C, J, and F or by regulating either or both the speed of the motor and of the pumps E H and adjusting said valves. The passage of steam from the boiler through the pipe K may be controlled by the valve k. When this valve is open, steam is projected from the nozzle k' into the pipe connection J. The impact of the steam with the water from the heater raises the temperature of said water to the temperature of the water within the boiler and of the water proceeding from the boiler through the pipe connection C, with which water it mingle at the point of communication j' of the pipe connections J C and the receiving end of the mixer. The water being so heated, practically no diminution of the temperature of the boiler-water results from the incoming of the feed-water, while the purity of the water within the boiler is preserved. In Figs. 1 and 2 I have shown one form of my novel combined mixer and the eliminator, which I will describe, reference being had particularly to Figs. 2, 3, and 4 of the drawings. In said figures, L indicates the mixer as a whole; l l', concentric foraminated pipes or tubes; l², grooves or corrugations formed in the wall of the casing sur-

rounding said pipes, said corrugations preferably increasing in depth from the receiving end of the mixer (where their depth is substantially nothing) to a point approximate to the delivery end of the mixer; l^8 , a groove preferably of equal or of greater depth than the greatest depth of the corrugations l^8 ; l^9 , a petcock controlling the escape from the mixer of the liberated gases and air; l^{10} , a tubular member communicating at one end with the pipe l^6 , which latter is controlled by the valve l^7 , and at its other end communicating with and preferably supporting the foraminated concentric tubes l^1 in substantially concentric position to the casing surrounding said tubes.

When water sufficiently heated to bring into suspension its contained impurities enters the mixer through the pipe J and tube l and pipe C and tube l' , it will pass through the foraminations in said tubes, becoming thereby thoroughly mingled. As the water passes along through the mixer toward the delivery end thereof it will carry said freed air and gases toward said end, they being borne along in said grooves until they enter the pocket l^8 , at which point they will congregate, their further forward movement being arrested by the wall of said pocket nearest the delivery end of the mixer. As frequently as desired said air and gases may be discharged from the mixer through the petcock l^9 . Were these gases and air not eliminated from the water, but allowed to reunite therewith, the matters in solution prior to the liberation of the gases and free air would again become in solution. The advantage therefore of eliminating said gases and air from the liquid and delivering the water to the centrifugal separator, with its contained impurities held in suspension against all possibility of becoming again in solution, is obvious.

In the drawings I have illustrated one form of centrifugal device which may be employed to effect the purging of water from its suspended impurities whether they be of less or greater specific gravity than the water. Said device is specifically claimed, shown, and described in the United States Letters Patent No. 702,795, granted to me therefor on the 17th day of June, A. D. 1902.

Briefly describing said apparatus and its operation, D is the device as a whole; d , a drum; d' , partitions radially disposed within the drum and secured to the outer wall and to the hub d^2 thereof; d^3 , an annular member revoluble with the drum and secured to the partitions; d^4 , an outlet for impurities of greater specific gravity than is the water communicating with the discharge-passage d^5 ; d^6 , an outlet for purged water communicating at one of its ends with the discharge end of the drum and at its other end with the non-revoluble bowl-shaped chamber d^7 , which chamber communicates with the worm-pump E ; d^8 , fixed wings within the chamber d^7 ; d^9 , concentric outlet-passages for the dis-

charge of impurities of less specific gravity than is the water; d^{10} , an electric motor. The pump E , member d^{12} , partitions d' , and drum d are secured one to another and to the motor d^{13} , by which they are revolvably controlled, and rotate upon the ball-bearings d^{14} . Assuming the revoluble parts referred to to be revolving at a sufficiently high rate of speed and water containing impurities of both greater and less specific gravity than it possesses to be entering the separator, the said heavier impurities will be centrifugally moved toward the wall of the drum, where they will settle and be discharged from the bottom of the drum through the outlet d^4 and the discharge-passage d^5 , while the said lighter impurities will be centrifugally moved toward the center of the drum, whence they will enter the pipe d^9 through the apertures d^{10} , following which they may be discharged therefrom. The liquid thus freed from the heavier impurities upon the one side and the lighter impurities upon the other is rendered substantially pure between said points. Said purged water, by virtue of its specific gravity, the pressure caused by water entering the drum, and the positive action of the pump E , will pass through the annular outlet-passage d^6 (formed by the hub and the inner wall of the annular member d^3) into the fixed chamber d^7 , where its rotary motion will be arrested by the fixed wings d^8 . Thence it will enter the pump and be discharged therefrom through the pipe F to the water-receiving space G within the boiler. The rotary motion of the purified water being, as described, suddenly arrested by the fixed wings d^8 upon its entering the chamber d^7 , foam or froth will thereby be created upon it, which froth and extraneous matters that may possibly not have been discharged through the outlets d^4 d^{10} may be discharged through the pipe d^{11} , which communicates at one of its ends with said chamber. Again referring to the drawings, d^{15} d^{16} are valves respectively controlling the passages d^9 d^{11} , and c' a flared end of the pipe connection C .

The device of my invention is applicable to stationary, marine, locomotive, or to whatsoever kind or form of boiler.

The advantages of using purged water in boilers are too obvious to need explanation. The advantages of creating a forced circulation are many, among which the following may be stated: Steam can be "gotten up" in much quicker time than were the water within the boiler not given a forced circulation, and particles of extraneous matters of greater specific gravity than the water within the boiler are kept in constant movement toward the surface of said water, whence they may be drawn off into the separator and eliminated.

In Fig. 2 I have shown a valve m controlling the passage M . When for any reason it is desired to wash out the mixer L , if the valve m be closed and the valve l^7 be opened

water may be forced through the mixer and out through the pipe l^6 , carrying with it such deposits as may have accumulated in the mixer. This feature of my invention, while 5 not an essential one, is, however, important in that it supplies a means of effectively cleaning the mixer without necessitating its being taken apart.

It is obvious that instead of the foraminated 10 tubes l^1 these concentric foraminated passages may be formed of any suitable material, such as wire-gauze; that the foraminations in said tubes may be of any sufficient number; that any suitable number of these 15 combined mixers and eliminators may be employed; that there may be as many foraminated tubes as desired, and that the number, size, and form of the various parts of said mixer may be greatly varied without departing 20 from the principle of the invention; that any suitable centrifugal device which will operate under positive pressure to eliminate impurities suspended in water may be employed instead of that herein described; that 25 there may be as many centrifugal devices employed as desired; that any form of pump adapted to draw the purged water from the drum of the separator and deliver it to the boiler may be employed; that said pump need 30 not be connected to nor operated by the drum-revolving means; that instead of an electric motor any suitable drum-revolving means may be employed, as an engine and a pulley controlled by a belt or rope or gears 35 operated by said engine or a turbine-motor; that the pipe C may communicate with the mixer L and with the boiler at any suitable point; that said pipe may or may not be provided with a flared end c; that the skimmer 40 may be omitted, if desired; that the pipe connection F may communicate with the discharge end of the separator and with the water-receiving space of the boiler at any suitable point, and that the number, size, and 45 form of the various parts of the device may be changed without departing from the principle of the invention.

Having thus described my invention, what I claim as new, and desire to secure by Letters 50 Patent, is—

1. In a steam - generating apparatus, the combination of a separator adapted to eliminate freed air and gases from water, a pipe connection communicating at one of its ends 55 with said separator and at its other end with a source of hot-water supply, a second separator adapted to separately eliminate from said water the heavy and light impurities in suspension therein, and a pipe connection 60 communicating at one of its ends with the delivery end of said last-mentioned separator and at its other end with the water-receiving space within the boiler, substantially as described.

65 2. In a steam - generating apparatus, the combination of a boiler, a separator adapted to eliminate freed air and gases from water,

a pipe connection communicating at one of its ends with the surface water within the boiler, and at its other end with the receiving end of said separator, a second separator adapted to separately eliminate from said water the heavy and light impurities in suspension therein, and a pipe connection communicating at one of its ends with the exit end of 70 said last-mentioned separator and at its other end with the feed-water-receiving space within the boiler, substantially as described. 75

3. In a steam - generating apparatus, the combination of a boiler, a feed-water heater, 80 a separator adapted to eliminate from heated water the gases and air freed by the heating of said water, a pipe connection communicating at one of its ends with the surface water of the water within the boiler and at 85 its other end with said separator, a pipe connection communicating at one of its ends with said heater and at its other end with said separator, a pipe connection communicating at one of its ends with the steam dome or space 90 of the boiler and at its other end with said last-mentioned pipe connection, a second separator adapted to eliminate impurities in suspension in water, and a pipe connection communicating at one of its ends with the exit 95 end of said last-mentioned separator and at its other end with the feed-water-receiving space within the boiler, substantially as described.

4. In a steam - generating apparatus, the combination of a boiler, a feed-water heater, 100 a separator adapted to eliminate from heated water the gases and air freed by the heating of said water, a pipe connection communicating at one of its ends with said heater and at 105 its other end with said separator, a pipe connection communicating at one of its ends with the steam dome or space of the boiler and at its other end with the last-mentioned pipe connection at or approximate to the water-receiving end of said separator, and a second separator adapted to eliminate impurities in suspension in water, and a pipe connection 110 communicating at one of its ends with the exit end of said last-mentioned separator and at its other end with the feed-water-receiving space within the boiler, substantially as described. 115

5. In a steam - generating apparatus, a separator adapted to eliminate from heated water 120 the gases and air freed by the heating of said water, said separator being provided with a foraminated tube, substantially as, and for the purpose, described.

6. In a steam - generating apparatus, the combination of a boiler and a separator adapted to eliminate from heated water the gases and air freed by the heating of said water, 125 said separator being provided with a plurality of foraminated tubes, substantially as, and for the purpose, described.

7. In a steam - generating apparatus, the combination of a boiler and a separator adapted to eliminate from heated water the gases

and air freed by the heating of said water, said separator being provided with a plurality of substantially concentrically disposed foraminated tubes, substantially as, and for the purpose, described.

8. As an article of manufacture, a combined water-mixer and air and gas eliminator provided with a foraminated member, substantially as, and for the purpose, described.

10. 9. As an article of manufacture, a combined water-mixer and air and gas eliminator provided with a plurality of foraminated members, substantially as, and for the purpose, described.

15. 10. As an article of manufacture, a combined water-mixer and air and gas eliminator provided with a plurality of substantially concentrically disposed foraminated members, substantially as, and for the purpose, described.

20. 11. As an article of manufacture, a combined water-mixer and air and gas eliminator provided with a foraminated member and having longitudinal grooves in the wall of the 25 casing, substantially as, and for the purpose, described.

30. 12. As an article of manufacture, a combined water-mixer and gas and air eliminator having within its casing a foraminated member and grooves formed in the wall of the casing, which grooves have a greater depth at or 35 approximate to the water-exit end of the casing than at or approximate to the water-receiving end thereof, substantially as, and for the purpose, described.

35. 13. As an article of manufacture, a combined water-mixer and air and gas eliminator having a foraminated member within its casing, a plurality of longitudinal grooves in the 40 wall of the casing, and an annular groove or chamber approximate to the exit end of said

casing, substantially as, and for the purpose, described.

14. As an article of manufacture, a combined water-mixer and air and gas eliminator 45 having within its casing a foraminated member and in the wall of said casing grooves, which grooves terminate at or approximate to the exit end of the casing in an annular groove or chamber, substantially as, and for the purpose, described.

15. As an article of manufacture, a combined water-mixer and air and gas eliminator having within its casing a foraminated member and in the wall of said casing grooves, 55 which grooves terminate at or approximate to the exit end of the casing in an annular groove or chamber, and means communicating with said chamber whereby the air and gases accumulated therein may be liberated therefrom, substantially as, and for the purpose, described.

16. As an article of manufacture, a combined water-mixer and air and gas eliminator having within its casing a foraminated member and in the wall of said casing grooves, 65 which grooves terminate at or approximate to the exit end of the casing in an annular groove or chamber, and a petcock communicating with said chamber, substantially as, and for 70 the purpose, described.

17. In a combined water-mixer and air and gas eliminator, the combination of the following elements, viz.: a casing; foraminated members l , l' ; grooves l^2 , l^3 ; and gas and air 75 discharge means l^4 ; all arranged and disposed substantially in the manner, and for the purpose, described.
